CLAIM

The ornamental design for a solar cell box, as shown and described.

DESCRIPTION

FIG. 1 is a front, top and right side perspective view of a solar cell box design showing my new design.

FIG. 2 is a rear, bottom and left side perspective view of a solar cell box.

FIG. 3 is a front view of a solar cell box.

FIG. 4 is a rear view of a solar cell box.

FIG. 5 is a left side view of a solar cell box.

FIG. 6 is a right side view of a solar cell box.

FIG. 7 is a top view of a solar cell box; and,

FIG. 8 is a bottom view of a solar cell box.

The broken lines depict portions of the solar cell box that form no part of the claimed design.

Any shading and cross-hatching are not features of the design but are utilized to illustrate the surface contours of the solar cell box design in the drawings.
